UNITED STATES PATENT OFFICE

JOHN PRESTON MINTON, OF WHITE PLAINS, AND ABRAHAM S. RINGEL, OF BROOKLYN, NEW YORK, ASSIGNEES TO RADIO CORPORATION OF AMERICA, A CORPORATION OF DELAWARE

ELECTROACOUSTIC DEVICE

Application filed February 23, 1934. Serial No. 694,570.

Our invention relates to improvements in electro-acoustic devices. More specifically, our invention relates to sound reproducers of the so-called loud speaker type and to the incorporation of a plurality of sound reproducing elements in said sound reproducers. 5

Heretofore it has been the practice to provide loud speakers with only one vibratory element having a natural resonant frequency equal to the frequency of a note located substantially in the middle of the scale of notes it is desired to hear. With such an arrangement the middle notes of the scale are reproduced with sufficient clearness and volume; but the lower and higher notes are not reproduced with sufficient clearness and volume. 15

One of the principal objects of our invention is to increase the clearness and volume of all of the audible notes reproduced by a loud speaker and particularly the notes in the higher and lower registers. 20

Other objects of our invention are the elimination of interferences between the various reproducing elements incorporated in our loud speaker; and independent regulation of volume of sound emanating from the various sound reproducing elements. 25

Other objects of the invention will appear from the following description of our invention taken in connection with the accompanying drawings in which 30

Fig. 1 is a cross section view of one modification of our invention; 35

Fig. 2 is a plan view of the mechanism for actuating the diaphragms;

Fig. 3 is a cross section view of another modification of our invention;

Fig. 4 is a plan view of the mechanism for actuating the diaphragms; 40

Fig. 5 is a schematic diagram of electrical connections.

Referring to Fig. 1, the central member A 45 comprises a middle vertical portion 1 having a middle passage-way 2 and two outwardly extending portions 3 and 4. The portions 3 and 4 have internal passage-ways 5 and 6 respectively communicating with the middle 50 passage-way 2. The outward extremities

of the outwardly extending portions are externally threaded for a purpose to be later described. The upper end of the vertical portion 1 has a peripheral internal shoulder 7 formed in it for limiting the downward movement of a horn 8, which is held in frictional engagement in the vertical portion of the central member. 55

As the low and high frequency units B and C are substantially the same, except as to size, the diameter of the diaphragm of the low frequency unit being larger than that of the high frequency unit, a description of one will suffice for both. 60

The low frequency unit B comprises an enclosing cylindrical casing 9 open at its outer end and closed at its inner end by an integral closure member 10 terminating in an internally threaded nipple 11 for engaging the external threads of the outwardly extending portion 3 for securing the casing 9 thereto. Casing 9' of the high frequency unit C is similarly secured to the outwardly extending portion 4. 70

A peripheral shoulder 12 is integral with the enclosing casing 9 and is contained therein. The low frequency diaphragm 13, constructed of appropriate diaphragm material is spaced away from the closure member 10 by resting against the outer surface of the shoulder 12 and is held in engagement therewith by means of a clamping ring 14 and screws 15 passing through registering holes in the diaphragm and ring and being threaded in the body of shoulder 12. 75

The outer end of the casing 9 is internally threaded for the reception of a closure member 16 made of some suitable material such as brass, and having an integral inwardly extending flange 17 externally threaded for engagement with the internally threaded outer end of the enclosing casing. 80

The diaphragm actuating mechanism (of which Fig. 2 is a plan view) comprises a substantially U shaped permanent magnet 18 85 suitably secured to the inner surface of the closure member 16. The free ends 19 and 20 of the permanent magnet are joined together by magnetic bridging members 21 and screws 22. 90

The magnetic bridging members 21, which are composed of a plurality of similar laminations united together, have two integral pole pieces 23, 23 extending toward the diaphragm 13. Magnetizing coils 24, 24 are mounted on said pole pieces and held in place thereon by means of suitable insulated washers 25, 25. The operation of the diaphragm actuating mechanism being well known in the art, requires no description here. The leads from the coils 24, 24 and 24', 24' may be brought out through insulated bushings in the casings 9 and 9' respectively, or through the closure members 16 and 16' respectively, or the leads may be connected to insulated terminals mounted in casings 9 and 9' or the closure members 16 and 16'. As the specific manner of bringing out these leads forms no part of our invention, it is not deemed necessary to show any means for bringing them out in the drawing.

In general, the low frequency unit is capable of responding only to low frequencies and the high frequency unit only to high frequencies. This, of course, is the condition desired for the elimination of distortion of tone and interference between the units. This condition is obtained in the following manner. The passageways 5 and 6 are so configured as to prevent the passage of high frequency sounds and low frequency sounds respectively therethrough. Any undesired low frequency sounds from the high frequency unit are substantially prevented from combining with the desired low frequency sounds from the low frequency unit. Similarly, any undesired high frequency sounds from the low frequency unit are substantially prevented from combining with the desired high frequency sounds from the high frequency unit. The vibrating element of the low frequency unit may also be suitably proportioned and configured so as to minimize the production of high frequency harmonics thereby. Electrical means, described later, are also provided for preventing distortion and interference between the units. All of these various expedients for eliminating distortion and interference between the units may be used singly, all together, or in any desired combination.

The volume of tone from either unit may be controlled by adjusting the position of the pole pieces with respect to the diaphragm. This can be done by screwing the closure members 16 and 16' in or out. It is obvious that the volume of tone from one unit may be regulated independent of the volume of tone from the other unit and vice versa.

Referring to Fig. 3, which shows another modification of our invention, the cylindrical base D comprises a lower part 101 and an upper part 102. The lower part 101 has an outwardly extending flange 103 for im-

parting stability to the device and an upwardly extending peripheral shoulder 104.

The upper part 102 of the base D comprises a cylinder open at its upper end and partially closed at its lower end by the integral circular baffle plate 105 having an opening 106 in its center for a purpose to be later described. The upper part has a depending peripheral shoulder 107 registering with shoulder 104 of part 101. A low frequency diaphragm 108 constructed of suitable diaphragm material is clamped between the two shoulders 104 and 107 by means of counter sunk screws 109 passing through plain holes in shoulder 104 and threaded into registering holes in shoulder 107. The diaphragm is thus spaced away from part 101 and baffle plate 105 for the establishment of proper acoustic conditions. The parts of base D may be moulded out of brass, aluminum or some suitable alloy or may be made by pressing, spinning or any of the other well known methods.

A closure member E, made of brass, aluminum or any suitable alloy, comprises a base portion 110 of annular configuration, an integral upwardly extending cylindrical portion 111 terminating in an upwardly extending nipple 112 and an internal annular integral plate 113 separating the space contained within the nipple from the space contained within the cylindrical portion 111.

The diaphragm actuating mechanism F, a plan view of which is shown by Fig. 4, comprises an annular mounting plate 114 secured in an annular groove 115 in the lower surface of base portion 110 by counter sunk screws 116. A permanent magnet 117 substantially U-shaped in configuration is bridged at its extremities or poles by magnetic bridging members 118 and 119 having downwardly extending poles 118' and 119' respectively; and magnet bridging members 120 and 121 having upwardly extending poles 120' and 121' respectively. The permanent magnet, bridging members and non-vibrating non-magnetic circular plate 117' arranged for preventing the passage of sound from the diaphragm 108 thru the annular opening in 114, are secured together and to the annular mounting plate 115 by screws 122.

Coils 123 are mounted on the various poles 118', 119', 120' and 121' and held thereon by means of insulated washers 124. The leads from the coils may be brought out through insulated bushings 125 or any of the other well known methods in the art.

The downwardly extending poles 118' and 119' together with the coils mounted thereon extend into the opening 106 but do not entirely close the said opening. The ends of the poles are in suitable proximity to the low frequency diaphragm 108 to effect its operation.

The annular plate 113 is threaded internally for the reception of the externally threaded

nipple 126 which terminates at its lower end in an annular disc 127 having a downwardly extending circular shoulder 128 around its outer periphery. The high frequency diaphragm 129 is clamped between the lower surface of this shoulder and a circular clamping ring 130 by means of counter sunk screws 131. The nipple 126, annular disc 127 and shoulder 128 are so proportioned that the high frequency diaphragm is suitably spaced from the ends of the poles 120' and 121' to effect its satisfactory operation.

The upwardly extending nipple 112 has an internal peripheral shoulder 132 at its upper end for limiting the downward movement of a horn 133 within the nipple. The upper end of the nipple is threaded externally for the reception of the threaded flange 134 of the clamping member 135, which has an additional flange 136 engaging a peripheral ledge 137 incorporated in the horn 133 whereby the horn 133 is detachably secured to the closure member E.

Adjustment of the high frequency diaphragm 129 with respect to the pole pieces 120' and 121' is obtained by the following arrangement. The upper surface of nipple 126 is bevelled and bevelled teeth cut therein as shown at 138. These teeth are in engagement with teeth of bevel gear 139 fastened to a shaft 140 which extends through the nipple 112. The shaft 140 is loosely journaled thru the nipple to permit of some upward and downward motion of gear 139. A knurled knob 141 is secured to the protruding end of shaft 140 by means of a set screw 142. The distance between the high frequency diaphragm 129 and the pole pieces 120' and 121' is thus controlled by turning the knob 141.

The distance between the low frequency diaphragm 108 and the pole pieces 118' and 119' is adjusted by screwing the closure member E into or out of the upper part 102 of base D. It is thus obvious that the diaphragms may be adjusted independent of each other.

The full line arrows indicate the path of the low frequency sound waves produced by the vibration of the low frequency diaphragm 108. These sound waves pass through that portion of the opening 106 unoccupied by the pole pieces 118', 119' and the coils 123, through a plurality of constricted openings 143 in annular plate 114 and then through another plurality of constricted openings 144 in annular plate 113 into the horn 133. These openings are so configured as to substantially prevent: 1st—any high frequency sound from the low frequency unit entering the horn or high frequency unit, 2nd—any high frequency sounds entering the low frequency unit and 3rd—any high frequency sounds emanating from the lower surface of the high frequency diaphragm entering the horn. It is thus seen that distortion of the sound emanating from the horn is prevented and interfer-

ence between the units is substantially eliminated.

Referring to Fig. 5, which is a schematic diagram of electrical connections for our loud speaker, the coils 201 for actuating the low frequency diaphragm are connected in parallel; while the coils 202 for actuating the high frequency diaphragm are also connected in parallel. The coils 201 are connected across the output terminals of electrical filter 205, 70 while the coils 202 are connected across the output terminals of electrical filter 206. The filters 205 and 206 are connected in series across the input leads 203 and 204. The filter 205 has characteristics which permit the passage of low frequency currents corresponding to the low frequency notes thru the coils 201 and prevents the passage of high frequency currents corresponding to the high frequency notes thru the coils 201. The filter 206 has 75 characteristics which permit the passage of high frequency currents corresponding to the comparatively high frequency notes thru the coils 202 and prevents the passage of low frequency currents corresponding to the comparatively low frequency notes thru the coils 202. It is thus seen that we provide electrical means for preventing distortion and interference between the low frequency unit and the high frequency unit.

In order for the coils of a loud speaker to be actuated by maximum energy so that the volume of sound produced thereby is a maximum it is necessary that the impedance of the coils be as nearly equal to the impedance of the tube to which they are connected as it is possible to make them. The high frequency coils 202 are so designed that this impedance is substantially equal to the impedance of the tube at a frequency which occupies a middle position in the scale of notes of comparatively higher frequencies.

Similarly, we arrange the coils 201 of the low frequency unit to have an impedance substantially equal to the impedance of the tube 110 over the lower range of frequencies to which the low frequency unit is responsive. This will require more turns on the coils 201, which will give them a fairly high inductance. At the high frequencies the impedance 115 of coils 201 will become excessively high and thus tend to prevent passage of high frequency energy to the coils 202. The connection of the filter 205 to the coils 201, however, permits the free passage of high frequency currents thru the coils 202 so that the impedance of the entire system at the higher frequencies is largely determined by the impedance of coils 202. The impedance of the high frequency coils 202 is sufficiently 120 low at the low frequencies, so as not to appreciably influence the total impedance of the system. Thus a substantially constant impedance for the electro-acoustic system equal to the impedance of the tube is obtained over 125 130

a wide range of frequencies thereby insuring maximum energy output from the tube or its equivalent with consequent maximum volume of sound over a wide range of frequencies.

5 While we have shown the coils 201 and 202 connected in parallel, they might also be connected in series. The groups of coils might also be connected in parallel instead of in series as shown, without departing from the 10 spirit of the invention. In fact, the coils might be connected in a number of different ways without departing from the scope of the invention.

15 While we have shown only two sound reproduction units, we do not wish to be limited to such a number, but may employ as many as the results to be accomplished should demand.

20 While our invention is shown and described in connection with sound reproducers of the loud speaker variety, we do not limit ourselves to such devices but may also employ the principle of a plurality of diaphragms or 25 vibrating elements having different resonant frequencies in various types of sound transmitters and sound receivers.

25 While we have shown and described various preferred modifications of our invention, we do not limit ourselves to said modifications; but may employ such other embodiments as may come within the spirit and scope of our invention.

Having described our invention, what we claim is:

35 1. The combination of an audio frequency generator, an acoustic device, a plurality of electro-acoustic devices, each having a coil, each of said coils being responsive to a characteristic vibration frequency and having an 40 impedance substantially equal to the impedance of the generator at the respective vibration frequency of each coil, whereby maximum value of sound is produced.

45 2. In combination a plurality of electro-acoustic devices having different size diaphragms each of said electro-acoustic devices being provided with separate passages constructed selectively to conduct separate vibration frequencies, and a single acoustic 50 device through which such separate vibration frequencies are transmitted.

55 3. In combination, a vacuum tube amplifier having an output circuit, a plurality of electro-magnetic reproducers connected to said output circuit, each of said reproducers having a coil and the impedance of said coils being substantially equal to the impedance of said vacuum tube over the range of frequencies for which said reproducers are 60 designed to operate.

65 4. In combination, a vacuum tube amplifier having an output circuit, a first filter connected to said output circuit, a second filter connected to said output circuit, a first electro-magnetic reproducer having a coil con-

nected to said first filter, and a second electro-magnetic reproducer having a coil connected to said second filter, the impedance of said coils being substantially equal to the impedance of said amplifier over the range 70 of audible frequencies.
